Patented Nov. 21, 1922.

Inventor,
Kurt Wandel

By his Attorney

Clyde A. Rogers

UNITED STATES PATENT OFFICE.

KURT WANDEL, OF NEW YORK, N. Y., ASSIGNOR, BY MESNE ASSIGNMENTS, TO ARKELL SAFETY BAG COMPANY, OF NEW YORK, N. Y., A CORPORATION OF NEW YORK.

MANUFACTURE AND CRINKLING OF PAPER.

Application filed April 6, 1920. Serial No. 371,577.

To all whom it may concern:

Be it known that I, KURT WANDEL, a citizen of Wurtemberg, who have declared my intention of becoming a citizen of the United States, and resident of New York city, county of New York, State of New York, have invented an Improvement in the Manufacture and Crinkling of Paper, of which the following description, in connection with 10 the accompanying drawings, is a specification, like characters on the drawings representing like parts in each of the several views.

This invention relates to the manufacture 15 of paper and the crinkling thereof to render the same stretchable. More particularly the invention has to do with an improvement in crinkled paper manufacture wherein a crinkling device equipped with a suction 20 roll crinkling drum is employed associated with, and in combination with, a paper mill or with an apparatus for finishing or treating paper. It is not new to combine a paper crinkling device with a paper mill to crinkle 25 the freshly made paper but in the prior art so far as known to me, the crinkling apparatus available has required that the paper web be subjected to its operation while it is still very soft and tender, i. e., before it is 30 subjected to the action of the drier rolls. On account of the delicacy and weakness of the paper at this stage, this limitation has very materially reduced the speed at which the paper mill could be operated to produce 35 crinkled paper, and the manufacture of crinkled paper at the mill has thus involved an economical loss in lowering the capacity of the mill as a whole. Further, paper crinkled at this stage of its manufacture, 40 i. e., before it is compacted and calendered by the driers is not so tough and strong as the same paper would be had it gone through the drier system. Still further, when the paper is crinkled after it comes from the 45 last press roll and before it enters the drier system, it is caught between the drier felt of the drier drums and the fresh made crinkles are largely flattened down and pressed back into the web so that the stretch- 50 able quality of the paper cannot be made use of so readily. I have found that by the use of a crinkling device equipped with a suction roll crinkling drum, the paper may be crinkled satisfactorily after it has passed 55 through most, or all, of the drier system, and

thereby I am enabled to obtain the advantage of the driers in calandering and strengthening the paper so that the crinkled paper produced is a much stronger and more satisfactory product, and since the paper when 60 it leaves the crinkling device is largely calendered and dried it is tough and strong enough so that no reduction in the normal speed of the paper mill is required. The foregoing and other objects and advantages 65 of the invention will more fully appear from the following detailed description, and the distinctive features of novelty will thereafter be pointed out in the appended claims.

The drawing shows a diagrammatic side 70 elevation, illustrating the application of the invention to an ordinary Fourdrinier paper machine.

Referring to the drawing 10 indicates the system of press rolls and felts of the machine by which the paper web is made into a coherent sheet. 10^a indicates the final set of press rolls from which the paper web W is transferred to the system of drier drums 11. The paper web at this stage is still very 80 soft and delicate and still saturated with moisture. In accordance with my invention, instead of creping the paper at this point as has heretofore been the common practice, the paper is run through a substantial part 85 of the drier system, preferably through the major portion thereof, so that most of the moisture is extracted therefrom and the paper condensed and calendered, and thus made relatively strong and tough, and sub- 90 substantially finished. From these driers the web is led onto a crinkling drum 12 which is in the form of a rotarily driven suction roll produced as a hollow shell with multiple 95 perforations throughout the operative extent thereof adapted to communicate with a suction box 13 stationarily mounted within the shell just back of the point at which the paper is crinkled or creped. A suitable doctor or clearer 14 is mounted for co-operation 100 with the crinkling drum to clear the paper therefrom while the paper is held adherent to the surface of the drum by the suction action, to produce a crinkled web as indicated at W'. The structure and manner of 105 operation of this suction roll or crinkling device is more fully shown and claimed in my earlier application, Serial Number 346,066, filed December 19, 1919. With the use of such a suction roll crinkling device the paper 110

may be crinkled in a practicable and satisfactory manner when it is nearly or substantially dry and hence it is possible to locate this crinkling device so as to handle the 5 paper after it has passed through the major portion of the drier system. Thence the crinkled web W' may be led around another portion 11^a of the drier system to complete the drying out of the paper and then led 10 onto a take-on roll 15 or otherwise taken care of.

I am aware that the invention may be embodied in other specific forms without departing from the spirit or essential attributes thereof, and I therefore desire the present embodiment to be considered in all respects as illustrative and not restrictive, reference being had to the appended claims rather than to the foregoing description to 15 indicate the scope of the invention.

Having described my invention what I claim as new and desire to secure by Letters Patent is;

1. The combination with a machine for 25 making a paper web including drier mechanism, of crinkling mechanism disposed and arranged to act on the paper web after it has passed through a substantial part of said drier mechanism, and including a crinkling

drum formed as a suction roll and having a 30 suction box co-operative therewith.

2. The combination with a machine for making a paper web, and including a drier system, of crinkling mechanism disposed and arranged to act on the paper web after 35 it has passed through a substantial part of said drier system, and including a crinkling drum equipped with means for causing the paper web to adhere to it by air suction.

3. The combination with a machine for 40 making a paper web including drier mechanism, of crinkling mechanism arranged and disposed to act on the paper web after it has been acted on by said drier mechanism and including a crinkling drum with a doctor 45 co-operative therewith, said crinkling drum equipped with means for causing paper to adhere to it by air suction.

4. The combination with a paper making machine for making paper in the web of a 50 crinkling mechanism operating on the freshly finished paper, said mechanism comprising a crinkling drum and pneumatic means for causing the paper web to adhere to the crinkling drum. 55

In testimony whereof, I have signed my name to this specification.

KURT WANDEL.
